UNITED STATES PATENT OFFICE.

PAUL AUSTMAN, OF ST. LOUIS, MISSOURI.

MUSICAL NOTATION.

SPECIFICATION forming part of Letters Patent No. 393,054, dated November 20, 1888.

Application filed December 20, 1887. Serial No. 258,528. (No model.)

To all whom it may concern:

Be it known that I, PAUL AUSTMAN, of St. Louis, in the State of Missouri, have invented a new and Improved System of Music, of 5 which the following is a full, clear, and exact description.

This invention aims at facilitating the art of playing key-board instruments, and enables singers to sing at sight quickly. It removes to nine-tenths of the difficulties found in reading, writing, thinking, and playing or singing music, and is easily mastered by both performer and vocalist.

My invention consists in the peculiar arrangement of the staff.

In the drawings, Figure 1 is a major scale on the new music system with permanent syllable names, (the second and seventh being changed for obvious reasons.) Figs. 2 and 3 show my method of writing notes without a prepared staff or beyond the same. Fig. 4 represents improved sharp and flat notes. Fig. 5 has the common chord of various keys written uniformly by the new method. Figs. 25 6 and 7 show the simplicity of the improved method as compared with the old.

In my arrangement the middle of the staff is designated by a heavy division-line, H, two lines on each side of which will form a staff of 30 four lines and four spaces for notes. This arrangement of the staff has very great advantages over the old staff—as, for instance, in the old plan the same note written on a line in one octave will be in a space the next higher 35 or lower octave, and vice versa. This change of lines with spaces takes place with every primitive note in every different octave invariably in both the so-called "G" and "F" clefs. In my system there is but one position for 40 every primitive note, line, or space, and the octaves above or below will have a like position, and will be equally distant from their "tetrameters" or heavy lines, by which their (relative) pitch is to be ascertained. In the 45 ordinary notation every note must be learned anew in each successive octave and again in each clef, for reasons above stated, while the key-note, with its relative scale, wanders up or down with the assistance of sharps and 50 flats to retain the relations in the different keys, causing an almost insurmountable obstruction to performing music intelligently.

Music written by my improved notation has successively 1 2 3 4 below and 5, 6, 7, and 8 above heavy line in all keys and in all octaves— 55 in the treble and in the bass. The heavy line H, on which no notes are written, divides the scale into its natural tetrachords or half-scales. The bass is indicated by placing the "clef" or octave-sign one space lower for one and two 60 spaces lower for two octaves, &c. In like manner the treble may be raised one or more octaves, Fig. 2. Accidental notes I represent by notes differently formed, which makes the natural unnecessary. Long accidental notes 65 are represented by ovals written vertically—the augmented by a full (O) and the flattened by a half (D) oval. Short accidentals are given by an oblique cross (X) for the sharp and one-half of the same (<>) for flat notes, Fig. 4, K 70 L M N.

That all music be written in one standard key is very desirable, since every octave is capable of two hundred and sixty-four transpositions in the major and minor keys, the 75 same being so many and so complex that by the old method all keys are mastered only by experts. According to the new method all music is represented by a standard position, and a transposition key-board is used to render it properly on the instrument. The key of a piece of music is marked at the beginning, and the absolute pitch of "middle C" is indicated by a small note, O, near the bottom 80 treble clef, making it easy to adjust the transposition key-board, and showing whether the absolute pitch of the music is written high or low. The notes written on the lower line of the treble clef are the key-notes from G below middle C to F above it, thus varying the formal or relative pitch not more than two and one-half steps from the real or absolute pitch, except in the keys of F-sharp and G-flat, which 85 will be three full steps from the key of C. 90

Instead of the common names of notes and 95 pauses indicating their length, I use the following: $\textcircled{Q}$, hu; $\textcircled{J}$, ha; $\textcircled{J}$, ho; $\textcircled{J}$, he; $\textcircled{A}$, hi; $\textcircled{A}$, h', (pronounced hoo, häh, hö, hä, hi, h'.) If a dot is placed after the note or pause, short "i" is added, thus: $\textcircled{J}.$, hoi, (pronounced hö-i.) 100 To indicate the movement I use the Roman figures I to VII. I denotes grave; IV, moderate; VI, allegro; VII, presto.

I am aware that patents have been granted

for systems of notation with three lines and two spaces, with five lines and four spaces, the key-note on a heavy line or wide space, or the reverse, with lines only for notes, and also with spaces only for notes.

What I claim as my invention, and desire to secure by Letters Patent, is—

A music-sheet provided with a staff of four

lines and four spaces for notes, with a heavy division-line in the middle, substantially as to above set forth.

PAUL AUSTMAN.
